UNITED STATES PATENT OFFICE.

CHARLES THOMAS MASON, OF SUMTER, SOUTH CAROLINA, ASSIGNOR, BY MESNE ASSIGNMENTS, TO SPLITDORF ELECTRICAL COMPANY, OF NEWARK, NEW JERSEY, A CORPORATION OF NEW JERSEY

IGNITION SYSTEM.

1,207,193.

Specification of Letters Patent.

Patented Dec. 5, 1916.

Application filed April 7, 1915. Serial No. 19,758.

To all whom it may concern:

Be it known that I, CHARLES THOMAS MASON, a citizen of the United States, residing at Sumter, in the county of Sumter and State of South Carolina, have invented certain new and useful Improvements in Ignition Systems, of which the following is a specification, reference being had to the accompanying drawing.

10 My invention relates to ignition systems for internal combustion engines and more particularly to that type in which the magneto windings are energized by the operation of the magneto or an auxiliary source 15 of current or both.

An object of the invention is to provide an arrangement of circuits and apparatus whereby the primary winding of a magneto, such as that shown in the patent to Mason 20 No. 1,103,361 issued July 28th, 1914, may be energized by current from an auxiliary source through a current varying device which when connected will operate continuously and unaffected by the operation of 25 the magneto.

Another object of the invention is to provide an arrangement of the above type in which the magneto unit and the auxiliary energizing means may be readily connected 30 and disconnected without disarranging the magneto parts.

A further object of my invention is to provide a circuit arrangement whereby an auxiliary source of current may be connected with 35 the primary winding of a magneto of the type above mentioned through a vibrator and controlled by the usual timing contacts of the magneto without affecting the continuous operation of the vibrator.

40 Other objects of my invention will be apparent from a perusal of the following specification and accompanying drawings.

My invention is illustrated in the accompanying drawings, in which:

45 Figure 1 is a diagram showing the magneto parts, the auxiliary energizing means and the various circuit connections. Fig. 2 is a diagram showing the external connections between the various apparatus. 50 Fig. 3 is a schematic diagram of the circuits.

Referring to the drawings in particular, 1 indicates the permanent magnet field structure having rotatable pole pieces 2-3 of constant polarity carried on an operating

shaft 18. The armature core structure 17 has its polar extensions in operative relation to the rotatable field pole pieces and is adjustable about the axis of rotation of the same. Primary and secondary windings 4 and 5 respectively are carried by the armature core in inductive relation to each other, the secondary winding having one terminal connected to frame or ground 16 and the other terminal connected to the insulated contact of a translating device or spark plug indicated diagrammatically at 6, the other terminal of which is connected to frame or ground 16 in a manner well known in the art, while the primary winding has one terminal connected to ground 16 and the other terminal connected to the terminal 8, both terminals of the primary coil being bridged by a condenser 7. The terminal 8 is electrically connected with the contact 19 of a pair of make and break contacts 19-9. The contact 9 is adapted to be moved into and out of contact with the normally stationary contact 19 by means of a suitable cam 10 connected with the magneto shaft 18. The contact 9 is electrically connected to ground 16 and both the contacts are provided with a casing 20 (Fig. 2), the casing, contacts and armature structure being adjustable as a whole about the axis of rotation of the rotatable pole pieces for purposes of timing, all as clearly described and illustrated in the above mentioned patent to Mason. An electrical coupling device such as a binding post or lock-nut 28 is mounted on the casing 20, but insulated therefrom, and electrically connected with the terminal 8 of the stationary contact 19, which contact is insulated from the magneto parts. The purpose of this coupling device 28 is to afford ready connection of the magneto circuit with the auxiliary energizing means which consists of an electromagnetic vibrator having the vibrating interrupter contacts 22 mutually controlling and operated by electromagnet 14, in a well known manner, and having a condenser 23 bridged across the contacts 22. A suitable source of current supply such as the battery 15 is provided for operating the interrupter. One pole of the battery 15 is connected to the ground 16 while the other pole is connected to the stationary member of the vibrator contacts 22. The movable member of the

vibrator contacts 22 is connected as shown to one terminal of the interrupter magnet 14, the other terminal of said magnet being connected to the movable contact of a switch 12. Connection is made from the stationary contact of the switch 12 through conductor 11 to the coupling device 28.

With special reference to Fig. 3 it will be seen that with the switch 12 closed as shown 10 the vibrator circuit will be completed for continuous operation of the vibrator, independently of the magneto or the actuation of the contacts 19-9, over the following path: battery 15, vibrator 13, switch 12, conductor 15 11, terminal 8, primary winding 4 through ground 16 and back to battery 15, if the contacts 19-9 are open, and if closed, the current path will be short-circuited from the terminal 8 through the contacts 19-9 to 20 ground 16.

In practice, the entire system may be arranged as shown in Fig. 2, the coupling device 28 being the only addition to the usual magneto. The conductor 11 may connect 25 to the coupling 28 and the switch 12 and interrupter 13 may be connected as separate pieces of apparatus as shown, although it is obvious that these may be combined in one unit. It will be further observed that 30 reversal of the wires at the magneto or between any of the various pieces of apparatus will have no effect on the operation of the system, it being necessary merely to place the magneto switch, interrupter, and 35 battery in series.

In operation, the switch 12 being closed, the interrupter circuit is completed over the following path: battery 15, vibrator 13, switch 12, conductor 11, coupling 28, contacts 19-9, through ground 16 and back to battery 15. The dynamo shaft being slowly turned over as is the case when starting, the contacts 19-9 are separated at the proper time, thus opening the shunt between the 40 conductor 11 and ground 16 and permitting the interrupted current to flow through the primary winding 4 over the circuit previously described. This interrupted current in the primary winding induces a current in the secondary winding 5 which produces a continuous train of sparks at the spark plug 6 as long as the contacts 19-9 remain open. It will be seen that the interrupter 13 operates continuously regardless 45 of whether the contacts 19-9 are opened or closed but that the opening and closing of said contacts determine the time at which the spark is produced at 6, so that the timing of the spark, in starting on battery, 50 may be effected by adjustment of the casing 21 in the same manner as when the magneto alone is used for ignition. The engine having been started, the magneto shaft is rotated at sufficient speed to operate the magneto for alone effecting ignition, and the 55

switch 12 may then be opened to disconnect the vibrator.

While I have herein shown and described the preferred embodiment of my invention, I wish it to be understood that I do not 70 limit myself thereto but contemplate all such modifications as fairly fall within the scope and purview of the appended claims.

Having thus described my invention, what I claim and desire to secure by Letters 75 Patent is:

1. An ignition system for internal combustion engines comprising in combination the following instrumentalities: a magneto having a permanent magnet field structure 80 with rotatable pole pieces of constant polarity carried on an operating shaft, a normally stationary armature core having pole pieces extending into operative relation with said rotatable pole pieces and adjustable 85 about the axis of rotation thereof, a pair of interrupter contacts operated by a cam connected to the shaft, one of said contacts being stationary in relation to the armature core and insulated from the magneto parts 90 and the other of said contacts being operated by the cam and normally grounded, a casing for the said cam and interrupter contacts, said casing and contacts being adjustable as a whole with the said armature 95 core during operation, a circuit coupling device carried on the outside of the casing and electrically connected with the said insulated contact, a primary winding on the armature having one terminal connected to ground 100 and the other terminal connected to the said insulated contact, a secondary winding on the armature core having one terminal grounded and the other terminal connected to the insulated electrode of a spark plug, 105 a condenser bridged across the terminals of the primary winding, an electromagnetic interrupter, an electric battery having one terminal grounded and the other terminal connected with one terminal of said interrupter, 110 a circuit connecting the other terminal of the interrupter with the said circuit coupling device and a switch included in said circuit.

2. An ignition system for internal combustion engines comprising in combination the following instrumentalities: a magneto having a permanent magnet field structure with rotating pole pieces of constant polarity, an operating shaft therefor, a normally stationary armature core having pole pieces extending into operative relation with said rotatable pole pieces and adjustable about the axis of rotation of the said rotatable pole pieces, a primary winding on the armature core having one terminal grounded and the other terminal connected to a normally stationary insulated contact, a grounded movable contact adapted to coöperate with said insulated contact and to be moved into and 115 120 125 130 135

- out of contact therewith by a cam connected to the operating shaft, said contacts being adjustable as a whole at any time with the armature core, a casing for said cam and contacts fixed to the armature core so that adjustment of said armature core and contacts may be effected by movement of the casing, an insulated circuit coupling device carried on the outside of said casing and electrically connected with the said insulated contact, a secondary winding on the armature core having one terminal grounded and the other terminal connected to a translating device, an electromagnetic current varying mechanism operative independently of the magneto, a source of current supply independent of the magneto and circuit connections connecting the said source of current through the current varying device to the said circuit coupling device. 15
3. An ignition system for internal combustion engines comprising in combination the following instrumentalities: a magneto having a permanent magnet field structure with rotating pole pieces of constant polarity, an operating shaft therefor, a normally stationary armature core having pole pieces extending into operative relation with said rotatable pole pieces and adjustable about the axis of rotation of the said rotatable pole pieces, a primary winding on the armature core having one terminal grounded and the other terminal connected to a normally stationary insulated contact, a grounded movable contact adapted to coöperate with said insulated contact and to be moved into and out of contact therewith by a cam connected to the operating shaft, said contacts being adjustable as a whole at any time with the armature core, a casing for said cam and contacts fixed to the armature core so that adjustment of said armature core and contacts may be effected by movement of the casing, an insulated circuit coupling device carried on the outside of said casing and electrically connected with the said insulated contact, a secondary winding on the armature core having one terminal grounded and the other terminal connected to a translating device, an independent source of variable current supply connected to said circuit coupling device and a switch included in the circuit of said source of supply for opening and closing the same. 40
4. An ignition system for internal combustion engines comprising in combination the following instrumentalities: a magneto having rotatable field pole pieces of constant polarity, an operating shaft therefor, a normally stationary armature core structure having pole pieces extending into operative relation with the rotatable field pole pieces and adjustable about the axis of rotation thereof, make and break contacts operated by a cam connected to the operating shaft, said contacts being adjustable as a whole with the armature core for timing purposes, a primary winding on the armature core having its terminals connected across said interrupter contacts, a secondary winding on the armature core in inductive relation to the primary winding and connected in circuit with the translating device, an electromagnetic vibrator operated independently of the magnetic circuit of the magneto, an independent source of current supply, an electrical switch and an electrical circuit connecting said source of current supply vibrator and switch in series across the terminals of the primary winding. 45
5. An ignition system for internal combustion engines comprising in combination the following instrumentalities: a magneto having a permanent magnet field structure with rotating pole pieces of constant polarity, an operating shaft therefor, a normally stationary armature core structure having pole pieces extending into operative relation with the rotatable field pole pieces and adjustable about the axis of rotation thereof, make and break contacts operated by a cam connected to the operating shaft, said contacts being adjustable as a whole with the armature core for timing purposes, a primary winding on the armature core having its terminals connected across said interrupter contacts, a secondary winding on the armature core in inductive relation to the primary winding and connected in circuit with the translating device, an electromagnetic vibrator operated independently of the magnetic circuit of the magneto, an independent source of current supply, an electrical switch and an electrical circuit connecting said source of current supply vibrator and switch in series across the terminals of the primary winding. 50
6. An ignition system for internal combustion engines comprising in combination the following instrumentalities: an ignition dynamo having an adjustable core structure carrying primary and secondary windings, interrupter contacts connecting the terminals of the primary winding and operated by a cam on the magneto operating shaft, said contacts being adjustable along with said core structure with relation to the shaft for the purpose of timing, a casing inclosing said contacts and adjustable therewith, a circuit coupling device on said casing connected to one of said contacts, and means for producing variable current operative independently of the magneto and connected to said coupling device across the terminals of the primary coil. 55
7. An ignition system for internal com-

- combustion engines comprising in combination the following instrumentalities: a magneto having an adjustable core structure carrying primary and secondary windings, a 5 translating device included in the secondary winding, a pair of interrupter contacts connecting the terminals of the primary winding operated in unison with the magneto and adapted to be adjusted along with said core 10 structure in any well known manner for timing purposes; a casing inclosing said contacts and adjustable therewith, a circuit coupling device on said casing connected to one of said contacts, and means for supplying 15 variable current operative independently of the magneto connected to said coupling device and adapted to be placed in circuit across the terminals of the primary winding at will.
- 20 8. An ignition system for internal combustion engines comprising in combination the following instrumentalities: a magneto having an adjustable core structure carrying primary and secondary windings, a 25 translating device included in the secondary
- winding, a pair of interrupter contacts connecting the terminals of the primary winding operated in unison with the magneto and adapted to be adjusted along with said core structure in any well known manner 30 for timing purposes, a casing inclosing said contacts, a coupling device on said casing connected to one of said contacts, an electromagnetic vibrator having interrupter contacts and operative independently of the 35 magneto, an electrical circuit including an independent source of current, said vibrator, the energizing circuit of the vibrator and an electrical switch in series connected to said coupling device and thereby placed across 40 the terminals of the primary winding, and the interrupter contacts, and a condenser bridged across the said vibrator contacts.

In testimony whereof I hereunto affix my signature in the presence of two witnesses. 45
